UNITED STATES PATENT OFFICE.

VINCENT DI MARZO, OF BENICIA, CALIFORNIA.

SELF-REGULATING LAMP.

SPECIFICATION forming part of Letters Patent No. 339,911, dated April 13, 1886.

Application filed July 30, 1885. Serial No. 173,081. (No model.)

To all whom it may concern:

Be it known that I, VINCENT DI MARZO, a citizen of the United States, residing at Benicia, in the county of Solano and State of California, have invented certain new and useful Improvements in Self-Regulating Lamps; and I do hereby declare the following to be a full, clear, and exact description of the invention, such as will enable others skilled in the art to 10 which it appertains to make and use the same.

The invention in this case relates to self-regulating lamps.

The object of my invention is to improve 15 and simplify the construction of that class of lamps which are provided with an oil-reservoir and a separate burner-supply regulating-chamber, whereby the cost of their manufacture will be less and their operation more sim- 20 ple and nearly perfect than heretofore.

The invention consists in certain details of construction of burner-supply regulating mechanism, and in securing the primary oil reservoir or chamber upon the tubular 25 supporting-standard of the lamp, as will be hereinafter particularly described.

In the accompanying drawings, forming 30 part of this specification, Figure 1 is a vertical section of a lamp embodying the invention. Fig. 2 is a detail view of the pipe above the reservoir when the invention is applied to a hanging lamp. Fig. 3 is a detail view of a suitable valve for the induction-orifice of the supply-tube.

35 A is the reservoir, which may be of any suitable size, shape, or style, and which is supplied with oil in any convenient manner, as through an aperture, a. It is to be understood that the aperture may be supplied with 40 a suitable cap or plug. The reservoir may be upon the lamp or elsewhere, and may be supplied with a gage-glass or any other suitable device, as with a float and chain or cord, a', as shown, to indicate the height of its con- 45 tents.

B is a pipe, which passes centrally, or substantially so, through the reservoir as the invention is here exhibited, and which thus forms the main support or the standard of the 50 lamp. The lamp may be either a suspension

lamp, a standing lamp, or a bracket-lamp to be attached to a wall, in any case the central tube preferably forming the standard by which the lamp is held in position.

In the present instance the invention is 55 illustrated as applied to a suspension or hanging lamp, so that chains or cords x are shown attached to the tube above the reservoir and passing over pulleys y to a counterpoise or ring, z, around or upon an outer tube in which 60 the central tube, B, slides.

Any other suitable means for raising or lowering a hanging lamp may be adopted without deviating from my invention.

In the illustration of the invention here 65 shown the central tube, B, passes vertically downward through the reservoir A into a separate regulator, C, consisting of an upper or float chamber, C', and a lower chamber, C''. Within the reservoir, and preferably at 70 a short distance above its bottom, the pipe B is provided with an aperture, b, for the admission of oil. The regulating-chamber or regulator C is of any desirable size, shape, or style, and is preferably suspended below the 75 reservoir A upon the pipe B, this pipe passing centrally through it. The float-chamber C' is provided with an appropriate bottom, c. Below the float-chamber the pipe B has an elbow, D, which is bent or curved upward 80 and enters the float-chamber through its bottom.

Within the float-chamber C', and placed upon the central pipe in such manner as to be free to move up and down thereon, is a float, 85 E. At the upper and lower part of this float are two rings, e, which form collars for the float upon the pipe, and by having these rings alone instead of an extended tube of the entire depth or even of a greater depth than the 90 float, which tube cannot always be straight, and by adjusting the size of the rings to the pipe, so that they will barely touch the same at two points, friction is reduced to a minimum.

Attached to the float, preferably near the 95 perimeter of the same, to give greater leverage, is a vertical rod, F, which may be adjusted in length to regulate the extent of its movement by a thumb-nut, f', or otherwise, and which is pivoted, as at f, to a horizontal bar 100

or lever, G. This bar or lever at its central part spans the tube B, where it has a wide collar or bend, to allow the free action of the lever on the valve as a handle. The rod F is so attached to the float as to move with it in both directions, and does not only move up with it as heretofore.

The extremity of the lever G, opposite its attachment to the rod F, forms a cap-valve, 10 H, which valve is over the induction-opening of the pipe D, where this pipe is tapered to lessen the orifice and form a seat for the valve. The lever G, carrying the valve, is hinged upon the induction tube or pipe D. The valve 15 H may be of any suitable kind; but I prefer to have it constructed in the nature of a cap having a central conical depression provided with a suitable washer, h, to fit over and upon the seat or tapered end of the pipe D. The 20 washer may be held in place by a packing-ring. It will be understood that the float rests in the liquid in the chamber C', and that as the liquid rises the float rises with it, and in this manner raises the rod F and operates the 25 lever G, which controls the valve and lessens or entirely stops the supply. Below the pipe D the pipe B is provided with a plug or stopper, b'.

Leading out from the bottom of the chamber 30 C' is a pipe, I, which joins the pipe B below the plug or stopper b'. The lower part of the pipe B, with which the pipe I communicates, leads to a distributor, J, which has leading from it the pipes K, which supply the burners L.

Instead of having the pipe B plugged, as at b', it may end below the pipe D, and there may be a separate pipe with which the pipe I communicates to feed the distributor; but 40 the construction shown is preferred, as being more compact.

Instead of having the pipe I and distributor J and pipes K, pipes may lead directly from the chamber C' to the burners, as shown in 45 dotted lines. It is obvious that as the oil is discharged to the distributor the valve over the induction-pipe will open.

There may be any number of burners. These may be arranged in any suitable manner, and the invention may be applied to any 50 suitable lamp.

It is evident that the supply-pipe might be outside of the regulator, as shown in dotted lines, in which case a rod might be placed in 55 the center of the chamber for the support or standard, along which the float would slide, and thus prevent it from catching against the sides of the regulator.

From the foregoing the operation of the device 60 shown will readily be understood, and

may be stated in sequence as follows: The reservoir having been supplied with oil, the same will enter the pipe B through the aperture b, and passing downward will run into the chamber C' through the bent pipe D. As 55 the oil enters the chamber C' it will raise the float E, and, as this carries up with it the rod F, it will operate the lever G, and close the valve. As the chamber C' is depleted by passage of the oil to the burners, the float sinks and the 70 valve is opened.

Having thus fully described my invention, what I claim, and desire to secure by Letters Patent, is—

1. In a lamp, the combination of the 75 tube B, a primary oil reservoir or chamber surrounding the same, a separate supply-regulating chamber having inlet and outlet openings, also surrounding the said tube, the two chambers communicating through the tube, 80 and a rod pivotally arranged in the regulating-chamber, provided at one end with the valve, and a float to which the rod is connected, substantially as described.

2. The combination, with the pipe or tube 85 B, a primary oil chamber or reservoir surrounding the same, and a separate supply-regulating chamber, also surrounding the tube B, the two chambers communicating through the pipe, of a float located in said regulating-chamber, surrounding and guided by the tube B, and a valve operated by said float to 90 open and close the inlet to the supply-regulating chamber, substantially as described.

3. In a lamp, the combination of the tube 95 B, a primary oil reservoir or chamber surrounding the same, a separate supply-regulating chamber having inlet and outlet openings, also surrounding the tube, the float situated in the regulating-chamber having the 100 collar e, surrounding and sliding upon the tube, and the valve-lever connected to the float and operating to open and close the inlet to the regulating-chamber.

4. The combination, in a lamp, of the central tube, B, the main reservoir and the separate supply-regulating chamber upon said tube and communicating therethrough by means of the opening b in the tube and inlet-tube D, a supply-outlet, and a valve operated 110 by a float in said supply-chamber to open and close the end of the inlet-tube, substantially as set forth.

In testimony whereof I affix my signature in presence of two witnesses.

VINCENT DI MARZO.
